UNITED STATES PATENT OFFICE.

WALTER MOORHOUSE, OF WEST NEW YORK, NEW JERSEY.

DESIGN FOR A CUSHION-HAMMER.

57,706.

Specification for Design. Patented Apr. 26, 1921.

Application filed May 7, 1920. Serial No. 379,684. Term of patent 7 years.

To all whom it may concern:

Be it known that I, WALTER MOORHOUSE, a citizen of the United States, residing at West New York, in the county of Hudson and State of New Jersey, have invented a new, original, and ornamental Design for Cushion-Hammers, of which the following is a specification, reference being had to the accompanying drawing, forming part thereof.

Figure 1 is a side view of the cushion hammer with a wood handle attached thereto,

Fig. 2 is an end view of the cushion hammer.

I claim:

The ornamental design for a cushion hammer, as shown.

WALTER MOORHOUSE. [L.S.]
